UNITED STATES PATENT OFFICE.

CHARLES WELLMAN CASSELS, OF HAMILTON, ONTARIO, CANADA, ASSIGNOR TO THE
N. SLATER COMPANY, LIMITED, OF HAMILTON, ONTARIO, CANADA.

CROSS-ARM.

Application filed December 6, 1923. Serial No. 678,965.

My invention relates to improvements in cross-arms for supporting transmission wires and more particularly multiple wire lines, and the object of the invention is to devise an improved form of metallic cross-arm which will be of simple and inexpensive construction, which may be very conveniently and quickly mounted upon the supporting pole as a single unit, and which will have exceptional strength and rigidity; a further object is to devise such a cross-arm which will provide ample clearance for all transmission wires carried thereby; and a still further object is to provide a construction using very few separate parts and reducing to a minimum the number of loose parts.

My invention consists essentially of a cross-arm comprising a horizontal and a vertical branch constructed and arranged all as hereinafter more particularly described and illustrated in the accompanying drawings in which:

Fig. 1 is a front elevation of my improved cross-arm, the relative position of a supporting pole being indicated in broken lines.

Fig. 2 is a side elevation of Fig. 1 looking in the direction of the arrow.

Fig. 3 is a section on the line 3, 3 of Fig. 1.

Fig. 4 is a section on the line 4, 4 of Fig. 1.

In the drawings like characters of reference indicate corresponding parts in the different views.

My improved cross-arm comprises the lower horizontal branch 1 and the upper vertical branch 2.

The horizontal branch 1 is formed from a length of rolled T-section, 3 being the web or stem portion of the section and 4 the flanges thereof.

The ends of the branch 1 are turned upwardly at 5 and are formed to receive the insulator supporting springs 6.

The vertical branch 2 is formed from two lengths of rolled channel sections 7 and 8 placed back to back (see Fig. 3) and secured together by rivets 9.

At the upper end of the vertical branch the channel sections are formed to receive the insulator supporting spring 10.

The channels 7 and 8 extend downwardly beyond their secured together portions, which secured together portions constitute the vertical branch of the cross-arm, towards

the horizontal branch and these extending portions are bent laterally away from each other to form the divergent inclined braces 11 and 12.

The lower ends of these braces lie on opposite sides of the web or stem 3 of the horizontal branch 1 and are secured thereto by rivets 13.

The vertical branch is provided with a bolt hole 14, and the horizontal branch is provided with a similar bolt hole 15 located centrally thereof through the web 3.

16 indicates in broken lines the relative position of a circular supporting pole on which the cross-arm is mounted.

Centrally of the horizontal branch 1 and on the side thereof adjacent to the pole 16 the flange 4 is deformed to form a concave seating 17 adapted to engage or straddle the pole as will hereinafter appear.

The construction and operation of my invention is as follows.

After the channels 7 and 8 have been suitably bent to form the divergent braces 11 and 12 and the upper ends formed to receive the insulator supporting spring 10, they are secured together back to back by the rivets 9. This completes the formation of the vertical branch.

The cross-arm is then completed by simply securing the horizontal branch 1 to the braces 11 and 12 by the rivets 13. This completes the formation of the cross-arm, and it will be noted that the portions 11 and 12 of the channels constitute cross-arm braces formed integrally with the vertical branch.

These divergent braces 11 and 12 are practically formed by bending what may be termed divided portions extending integrally from the lower end of the vertical branch.

The insulator supporting springs 6 and 10 are then mounted.

This completes the construction of the cross-arm which it will be noted comprises a simple unit having exceptional strength and rigidity.

The cross-arm is mounted upon the supporting pole 15 by simply passing two bolts through the orifices 14 and 15 and through the pole.

The deformed concave seating 17 engages the pole and does away with the necessity of

cutting the pole to receive the flange 4 at this point.

Thus there is no weakening effect upon the pole at this point.

5 This seating also increases the rigidity of the mounting upon the pole.

From the foregoing it will be noted that I have devised valuable improvements in cross-arms of this type.

10 Various modifications may be made in my invention without departing from the spirit of the invention or the scope of the claim and therefore the exact form shown is to be taken as illustrative only and not in a limiting sense.

For instance while I have illustrated the application of insulator supporting springs 6 and 10 this form of insulator mounting forms no part of my present invention and 20 any well known style of insulator mounting might equally well be employed.

What I claim as my invention is:

A metallic cross-arm of the class described comprising a horizontal branch and a vertical branch, the horizontal branch formed 25 from a length of metal of T-shaped cross-section with the web or stem portion directed towards the vertical branch, the vertical branch formed from two lengths of metal of channel shaped crosssection placed back 30 to back and secured together for a portion of their lengths, said channels extending beyond the aforesaid secured together portions towards the horizontal branch, and said extending portions bent to form divergent braces, the ends of which are secured to the web or stem portion of the horizontal branch on opposite sides thereof, the central portion of the flange of the T-shaped horizontal branch on one side thereof de- 35 formed to form a concave seating.

CHARLES WELLMAN CASSELS.
